[57] **CLAIM**

The ornamental design for a wrench extender, as shown and described.

DESCRIPTION

FIG. 1 is a front elevational view of the wrench extender of the present invention;

FIG. 2 is a rear elevational view of the wrench extender of FIG. 1;

FIG. 3 is a left side elevational view of the wrench extender of FIG. 1;

FIG. 4 is a right side elevational view of the wrench extender of FIG. 1;

FIG. 5 is a top plan view of the wrench extender of FIG. 1;

FIG. 6 is a bottom plan view of the wrench extender of FIG. 1; and,

FIG. 7 is a perspective view of the wrench extender of FIG. 1, the wrench shown in broken lines is for illustrative purposes only and forms no part of the claimed design.
